UNITED STATES PATENT OFFICE.

FRED. E. VOGEL, OF WATERBURY, CONNECTICUT, ASSIGNOR TO ROGERS & BROTHER, OF SAME PLACE.

DESIGN FOR A SPOON OR FORK HANDLE.

SPECIFICATION forming part of Design No. 12,452, dated September 6, 1881.

Application filed July 25, 1881. Term of patent 14 years.

To all whom it may concern:

Be it known that I, FRED. E. VOGEL, of Waterbury, in the county of New Haven and State of Connecticut, have invented a new Design for a Spoon or Fork Handle; and I do hereby declare the following, when taken in connection with the accompanying drawings and the letters of reference marked thereon, to be a full, clear, and exact description of the same, and which said drawings constitute part of this specification, and represent, in—

Figure 1, a front view; Fig. 2, a rear view.

This invention relates to a design for the ornamentation on the handles of spoons, forks, and like articles of table-service; and the invention consists in the ornamentation on the handle, as shown in the accompanying illustration.

Starting from its junction with the bowl, the handle is of equal width to about midway of its length, except directly at the bowl, where there is a swell upon each side. From the upper end of this part the handle gradually expands, terminating in segment shape at the tip, with a boss, *a*, at the junction of the two sections. Both the front and rear surface, at the tip, have a segment-shaped band corresponding to the shape of the end of the handle, the band consisting of beads on its upper and lower edge, with a series of rose ornaments on the face of the band. On the front and midway between the boss and tip is a transverse band, *b*, consisting of beads on the upper and lower edge, its surface ornamented by a series of star-shaped figures. At the lower end of the expanding part—that is, just above the boss *a*—there is a fan-shaped ornament, *c*, both on the front and rear, with a narrow semicircular

band above. On both sides, extending from the ornament *c* to the band at the tip, each edge is beaded. On the front these beads are interrupted by the ornamental band *b*. On the front, springing from the semicircular band below and extending on the surface toward the band *b*, is a floriated sprig, all as shown in the accompanying illustration. The rear differs only from the front in the omission of the band *b* and floriated sprig below.

I claim—

1. The design for one side of the spoon, consisting of the gradually-expanding part, terminating in segment shape, with a corresponding segment-shaped band at the tip, ornamented by beads on its upper and lower edges, with a series of rose ornaments on the face, the transverse band *b* below ornamented by a series of star-shaped figures, the sides of this part of the handle beaded from the semicircular ornament upward, as shown in the accompanying illustration.

2. The design for the reverse side of the spoon, consisting of the gradually-expanding upper part, terminating in segment shape, with a corresponding segment-shaped band at the tip, ornamented by beads on its upper and lower edges, with a series of rose ornaments on the face, the semicircular ornament *c* at the lower end of the said expanding part, with beads on the edges of the part extending from said ornament *c* to the segment-shaped band at the end, as shown in the accompanying illustration.

FRED. ED. VOGEL.
